LOCOMOTIVE DRIFTING AND
BY-PASS VALVEFrank Bukove, Albuquerque, N. Mex., assignor of
one-half to Leslie R. Kiehl, Raton, N. Mex.

Application October 1, 1934, Serial No. 746,465

2 Claims. (Cl. 121—133)

The invention relates to locomotives and more especially to the class of valves known as drifting valves which are used on locomotives.

The primary object of the invention is the provision of a valve of this character in association with a by-pass, wherein communication between the two ends of each cylinder of the locomotive is had for relieving pressure at one side of the piston and vacuum at the other side thereof when working within the cylinder when live steam is cut off to said cylinder and the steam throttle closed for the drifting of the locomotive, the valve being automatically controlled and assuring, in the working thereof, a free drifting of said locomotive.

Another object of the invention is the provision of a valve of this character, wherein the main steam throttle when actuated will automatically regulate the said valve so that the by-passing of cylinder atmosphere starts instantly by the closing of said throttle, and thus drifting of the locomotive is obtained with a minimum change in cylinder temperature.

A further object of the invention is the provision of a valve of this character, wherein on the closing of the main throttle valve, circulation of air and vapor from the compression side of the piston to the vacuum side during the entire stroke of the piston is had while the engine is drifting, and such valve is controlled by the main throttle valve which regulates the turning on or cutting off of steam to the cylinder of the locomotive and the flow of the live steam for the working of the piston in this cylinder is regulated by the steam chest valve in the usual or conventional manner, it being unnecessary and not required for any material change in the arrangement of the steam chest and the cylinder of the locomotive or the respective valve and piston working therein.

A still further object of the invention is the provision of a valve of this character in association with a by-pass, which is simple in construction, thoroughly reliable and effective in its operation, automatic in action, readily and easily accessible for inspection, repair or replacement, positive of operation, strong, durable, and inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a fragmentary front elevation of a locomotive, one steam chest and piston cylinder being in section to illustrate the application of

the drifting valve constructed in accordance with the invention.

Figure 2 is an enlarged sectional view on the line 2—2 of Figure 1 looking in the direction of the arrows and showing the drifting valves in their position when the main steam throttle is closed.

Figure 3 is a view similar to Figure 2 showing the position of the valves when the throttle is open.

Figure 4 is an inner face view of the valve chamber cover.

Figure 5 is a plan view of the valve cage.

Figure 6 is a plan view of the valve.

Figure 7 is an edge elevation of the cover shown in Figure 4.

Figure 8 is a side elevation partly in section of the valve cage as shown in Figure 5.

Figure 9 is a vertical longitudinal sectional view through the valve.

Similar reference characters indicate corresponding parts throughout the several views in the drawings.

Referring to the drawings in detail, particularly Figures 1, 2, and 3, the present invention is disclosed in connection with an engine cylinder A provided with what is commonly termed inside steam admission having a piston valve 10 operated by the valve rod 11 within the valve chamber 12 and having the steam space 13 communicating with the steam chest 14, which is located centrally between the ends of the cylinder. Steam ports 16 occur in the steam space and in the wall of the valve chamber, the ports being adapted to be closed by the valve 10 in certain positions thereof. Exhaust occurs in the wall of the valve chamber at the outer end of the valve at each extremity of the valve stroke and this exhaust is had through the exhaust channel 15 and smoke chamber of the locomotive in the usual manner. The steam ports 16 communicate with the passage 17, which surrounds the valve chamber bushing at these points, and communicate with their respective ends of the cylinder A through openings 18. As usual, the series of steam and exhaust ports are as one and occur in the circular wall of the valve chamber bushing, the ports being defined by the cyclic position of the valve respective to the said ports. That is to say, the valve moved to a direction of uncovering the ports on the steam space side permits the flow of steam to the cylinder. The valve moved to the opposite direction, these same ports close and are again uncovered on an opposite side of the valve, the spent steam in the cylinder escaping through these ports and out into the exhaust channel 15.

A piston 19 is shown operating within the cylinder A in the usual manner. The operation of the piston valve 10 in the valve chamber of

the chest 14 together with the connected parts and steam passages is common to all locomotives of the type shown during the application of the steam to the engine and the structure of these 5 parts may be considered common to locomotives of this type and typical of locomotive engines having the same function.

It is, of course, understood that an engine cylinder A is at each side of the locomotive and 10 likewise the steam chest 14 and it is to be understood that while in the following description and in what has preceded, reference is usually made to only one cylinder and one steam chest, etc., there are corresponding and duplicate parts 15 on the opposite side of the locomotive.

Provided adjacent to the cylinder A and parallel with the same and the steam chest 14 is a channel 35 having located near opposite ends and countersunk with respect thereto valve 20 spaces 20, these being confronted with valve cages 21 removably fitted in openings 22 accessible exteriorly and fitted with removable cover plates 23, the openings 18 being intersected by the spaces 20, so that the channel 35 at its ends 25 has communication with the cylinder A at opposite ends thereof and also with the steam ports of the valve chamber 12.

Arranged within these valve cages 21 are 30 drifting valves 24, the bottoms 25 thereof being adapted for engagement with seats 26 provided in said cages 21, while the tops 27 are adaptable for engagement with seats 28 interiorly of the said cages 21, these cages being formed with peripheral openings 29 and the said valves 24 being 35 of hollow formation and open at their tops and bottoms. Centrally fitted in these valves 24 are stems 30, the upper portions thereof being slidably fitted in center hub formations 31 on the cages 21, while the lower portions 32 of these stems 30 are passed through webs 33 and freely 40 slide therein, so that said lower ends 32 will project into steam pockets 34 and operate as pistons. The pockets 34 communicate with the steam space 13 by leads 37.

45 The cover plates 23 are removably secured in place by fasteners 36 and on their removal, access can be had to the cages 21 and also the valves 24.

The valves 24, when in the position as shown 50 in Figures 1 and 2 of the drawings, permit cylinder atmosphere to pass back and forth from one side of the piston 19 to the other through the channel 35 and this is effected when the main steam throttle is closed, resulting in the dropping of the steam pressure in the main 55 steam chest 14 and in the pockets 34 to zero, thus relieving the pressure of the steam against the lower ends 32 of the stems 30 of the valves 24, causing the latter to drop or become lowered for the opening movement thereof under their own 60 weight in conjunction with the suction action of the piston 19 in the cylinder A, the latter being in communication with the valve 10 in the steam chest 14. In the opening of the valves 24, these become unseated from the seats 26 and 28, so 65 that communication will be established through the passages 18 and the channel 35, these passages functioning as by-passes, and thus the atmosphere in the cylinder A is set free to flow and will move back and forth through the 70 passages 18 and channel 35 and thus equalize the valve steam chamber and cylinder condition, so that the piston 19 drifts, causing the interior atmosphere to flow through and around the drift

valves 24 to opposite ends of the cylinder A without drawing in exterior atmosphere through the exhaust passages 15.

When the main steam throttle is open, the 10 valves 24 will be lifted by the steam pressure in the pockets 34 acting upon the lower ends 32 of the stems 30 of such valves and these lower ends 15 functioning as pistons, so that live steam from the steam chest 14 will automatically operate said 20 valves 24 and thus shut off the by-passing of 25 atmosphere within the cylinder A from one side of the piston 19 to the other through the channel 35 and these valves 24 will remain closed or seated 30 against the seats 26 of the cages as long as steam is worked into the cylinder A for operating the 35 locomotive.

The leads 37 from the pockets 34 converge inwardly and upwardly into the steam space 13 in the chest 14. It should be apparent that the steam directed to the pockets 34 will play upon the ends 32 of the stems 30 and these ends 32 function as pistons for the valves 24 to lift the same under the pressure of the steam when the main steam throttle is open.

From the foregoing it is thought that the construction and manner of operation of the structure will be clearly understood and, therefore, a 25 more extended explanation has been omitted.

The invention is susceptible of various changes 30 in its form, proportions and minor details of construction and the right is herein reserved to make such changes as properly fall within the scope of the appended claims.

What is claimed is:

1. In combination with a locomotive cylinder 35 having a circulating conduit and a cored port communicating between the ends of the conduit and the cylinder; of a valve cage located at said port and in said conduit and a valve in said cage having a piston stem for controlling the valve by 40 steam pressure for permitting by-passing of cylinder atmosphere through said conduit from one end of the cylinder to the other, said cage having openings in its sides, a closed top and an open bottom, and said top having an opening for the 45 one end of the stem of the valve, a cap member through which said end of the stem passes removably securing the cage in position, said valve comprising a hollow member which is rounded inwardly from its ends to its center and which in 50 one position has its ends in contact with the closed top and open bottom edge of the cage and the second or lower end of the valve stem providing the piston therefor.

2. In combination with a locomotive cylinder 55 having a circulating conduit and a cored port communicating between the ends of the conduit and the cylinder; of a valve cage located at said port and in said conduit and a valve in said cage having a piston stem for controlling the valve by 60 steam pressure for permitting by-passing of cylinder atmosphere through said conduit from one end of the cylinder to the other, said cage having openings in its sides, a closed top and an open bottom, and said top having an opening for the 65 one end of the stem of the valve, a cap member through which said end of the stem passes removably securing the cage in position, said valve forming a seal with the cage above and below the side openings therein and the lower end of the 70 valve stem providing the piston for operating the valve.

FRANK BUKOVE.
